UNITED STATES PATENT OFFICE.

NATHAN M. LOWER, OF SCHENECTADY, NEW YORK, ASSIGNOR TO LOCOMOTIVE STOKER COMPANY, OF PITTSBURGH, PENNSYLVANIA, A CORPORATION OF PENNSYLVANIA.

LOCOMOTIVE-TENDER.

1,228,574.

Specification of Letters Patent.

Patented June 5, 1917.

Application filed January 18, 1916. Serial No. 72,693.

To all whom it may concern:

Be it known that I, NATHAN M. LOWER, a citizen of the United States, and resident of Schenectady, county of Schenectady, and 5 State of New York, have invented certain new and useful Improvements in Locomotive-Tenders, of which the following is a specification, and which are illustrated in the accompanying drawings, forming a part 10 thereof.

The invention relates to that type of locomotive tenders in which the fuel is in part carried on a deck above the water tank and back of the fuel bin; its object being to 15 provide improved means for moving the fuel forwardly on the deck in order that it may slide or be moved down the slope sheet at the rear end of the bin and come within easy reach of the fireman. 20 In its broader aspects the invention consists in a tender of the type defined, with a movable bulkhead at the rear of the deck and power means for drawing the bulkhead forward. It consists further in various de- 25 tails as hereinafter pointed out. In the accompanying drawings,

Figure 1 is a detail plan view of the improved tender;

Fig. 2 is a detail longitudinal vertical section of the tender, some of the parts being shown in elevation; and

Fig. 3 is a detail sectional view on the line 3—3 of Fig. 2.

The tender is represented at 10, and the 35 inner walls of its fuel bin at 11, 12. The bin is provided with the usual slope sheet 13 forming its rear wall, and from the upper end of the slope sheet extends the floor of the fuel deck 14, the rear end of the deck 40 being provided with a permanent wall 15.

A movable bulkhead 16 is located on the deck, and preferably, as shown, extends the entire width thereof. Before the deck is loaded with fuel this bulkhead is moved 45 back to the wall 15. As shown the bulkhead 16 is given the form of a carriage, having a bottom 17 and side walls 18, 19,—this carriage being provided with small wheels or rollers, as 20, 21, which run upon the floor 50 14 of the deck. The bottom 17 is provided with a downturned lip 22 at its forward end, which is substantially in engagement with the deck floor, and the side walls 18, 19, are provided with similar outstanding 55 lips at their forward ends, as shown at 23,

24, and which are substantially in engagement with the side walls of the deck, these walls forming continuations of the walls 11, 12. A guide rail 25, 26, may be attached to the walls 11, 12, and engaged by the carriage to prevent any tendency of the latter being tilted.

Power may be applied for advancing the bulkhead 16 in a variety of ways. In the structure disclosed there is shown for this 60 purpose a motor 27, mounted at the forward end of the deck and inclosed within a casting 28, which, in this instance, serves also to cover the upper end of a water conduit 29, such as is used in some instances in connection with a chute for filling the tender tank from a trough on the track. The motor 27 is shown as being adapted to drive a reciprocating fuel pusher 30, which moves over the slope sheet and carries the fuel 65 70 75 forwardly to the shoveling platform 31 of the tender.

The bulkhead is connected to the motor by means of cables 32, 33, these cables being shown as detachably connected to a cross-head of the motor piston by means of loops 34, hooked over pins 35. As shown, a second set of loops, as 36, is provided on the cables, and are adapted to be hooked over the pins 35 after the bulkhead has been 80 85 moved forward to some extent. The cables 32, 33, are preferably guided over pulleys, as 37, mounted at the forward end of the fuel deck. In practice the cables 32, 33, may be entirely disconnected from the motor when the tender is first loaded with fuel.

After the fireman has removed the fuel from the shoveling deck 31, he may set the motor 27 in motion and, by means of the 90 95 pusher 30, move the contents of the bin forward gradually to the shoveling floor. When the bin is empty he engages the hooks 34 at the forward ends of the cables with the pins 35, and a single forward movement of the motor piston will carry the bulkhead forward and thus move a part of the fuel from the deck into the bin. The motor may, if desired, be given a number of strokes for the purpose of pushing this 100 105 fuel down the slope sheet to the shoveling platform, the cables 32, 33, being slackened during the instroke of the motor. When more fuel is required from the deck, the loops 36 may be attached to the pins 35 and 110

the bulkhead 16 still farther advanced. Before reloading the tender with fuel, the bulkhead is moved back to the rear end of the deck by hand.

5. The motor 27 is preferably operated by steam, and a controlling valve is shown at 38 as being mounted on the forward end of the tender within convenient reach of the fireman. In the structure shown the forward movement of the bulkhead is limited by the casing 28. When the construction of the tender is such that this casing is not required, the bulkhead may, of course, be moved forwardly so as to discharge the 10 deck of the entire load.

Various changes in the form of construction may be made without departing from the scope of the invention.

I claim as my invention—

20. 1. In combination, a tender having a coal bin and a fuel deck back of the bin, and a bulkhead movable over the deck and adapted to advance the mass of fuel thereon.
2. In combination, a tender having a coal bin, a fuel deck back of the bin, a bulkhead movable over the deck and adapted to advance the mass of fuel thereon, and means for maintaining the bulkhead in upright position.
30. 3. In combination, a tender having a coal bin, a fuel deck back of the bin, and a bulkhead having a forwardly projecting floor and movable over the deck and adapted to advance the mass of fuel thereon.
35. 4. In combination, a tender having a coal bin, a fuel deck back of the bin, and a bulkhead having a forwardly projecting floor and side walls and movable over the deck and adapted to advance the mass of fuel 40 thereon.
5. In combination, a tender having a fuel

deck, and a bulkhead having a forwardly projecting floor, such floor having a downwardly and forwardly inclined lip at its forward end, and movable over the deck 45 and adapted to advance the mass of fuel thereon.

6. In combination, a tender having a fuel deck, and a bulkhead having a forwardly projecting floor and side walls, such floor 50 and walls having, respectively, downwardly and forwardly and outwardly inclined lips at their forward ends, and movable over the deck and adapted to advance the mass of fuel thereon. 55

7. In combination, a tender having a coal bin, and a fuel deck back of the bin, a bulkhead movable over the deck and adapted to advance the mass of fuel thereon, a motor at the forward end of the deck, and a cable 60 connecting a movable member of the motor with the bulkhead.

8. In combination, a tender having a fuel bin and a fuel deck back of the bin, a pusher reciprocable over a fuel supporting wall of 65 the bin, a motor for actuating the pusher, a bulkhead movable over the deck and adapted to advance the fuel thereon, and a cable for connecting the bulkhead with a member actuated by the motor. 70

9. In combination, a tender having a fuel bin and a fuel deck back of the bin, a pusher reciprocable over a fuel supporting wall of the bin, a motor for actuating the pusher, a bulkhead movable over the deck and 75 adapted to advance the fuel thereon, and a cable for connecting the bulkhead with a member actuated by the motor, such cable having a plurality of attaching means for engagement with such member.

NATHAN M. LOWER.
